UNITED STATES PATENT OFFICE.

FRANK J. GILROY, OF BUFFALO, NEW YORK.

SHOE FOR CAR DOORS.

Application filed September 4, 1924. Serial No. 735,938.

This invention relates to a device usable on cars having sliding doors which are in common use, and it is intended to lessen the chance of wrongful opening of freight cars 5 by removing the shoes secured to the body of the car and normally holding the closed door against being pried away from the car wall, at its lower side. Usually, analogous shoes are secured to the car by bolts, and not 10 infrequently dishonest persons remove the bolts and by swinging the lower side of the door outward obtain access to the car without breaking the car seal, and then by replacing the door, shoe and bolts, make detection difficult.

It is to be considered that while it is a simple matter to cut an opening into any wood or metal car, thieves of the class suggested avoid such expedients, for if detected 20 there is no explanation consistent with proper purposes on the part of an employee of the railway, as thieves sometimes succeed in obtaining such employment. If, however, a shoe can be removed with tools ordinarily carried by such employee for legitimate use, 25 it is very difficult to show criminal intent, since the employee usually claims that the car was found "in bad order", and he was merely trying to determine its safety and the 30 propriety of allowing it to leave the yard without thorough repair.

In the accompanying drawings,

Figure 1 is a side elevation of a portion 25 of a door, car wall, and a shoe in place thereon.

Fig. 2 is a section on the line 2—2, Fig. 1.

Fig. 3 is a plan view showing my guide fixed to a sill.

Fig. 4 is a section on the line 4—4, Fig. 1. 40 In these figures, A represents a car door, B a protecting plate on the outer face of the door's lower side, B' a car sill, R the body of a hollow upwardly open box-like shoe.

Primarily, this shoe is open above, only, 45 and in the plane of the door's path, and when in use with the door closed the opening is fully covered and closed by a lid R hinged at O, O', to swing upward about an 50 axis Y when the door has been opened, except for one shoe which engages the door in open as well as in closed position. This shoe must be attached before the door is hung, and it can afterwards be detached 55 only by removing first one of the door stops

and then the door, which could not be illegally done without betraying the thief. The inner wall of the box is rigidly fixed to the car body by bolts P having countersunk heads and passing outward through the car 60 sill, in which they cannot rotate, and through the rear wall of the hollow shoe, to receive nuts P', which being within the box are accessible only when the lid is raised, as it can be only when uncovered by the door. 65 The door being removed, the nuts of all the shoes may be unscrewed by the use of a suitable wrench.

The outer box wall extends upward to a point M and is laterally slightly rounded 70 outward or away from the door's path and is integral with large stiffening ribs C. The lids are curved on their free margins, as shown in Fig. 3, to fit the upwardly projecting outer wall of the box, from which, 75 however, they are spaced at N.

As shown, the car floor D is spaced from the door, but it is understood that when desired the device shown may be closed in any approved manner, or by means not concerned in this invention.

It will be observed that the countersunk heads of the bolts P afford no means for rotating the bolts, which in any case are not rotatable in the wood by any ordinary force. 85

As the guides are of malleable iron, they can, although not heavy, hardly be injured by accident or design, and cannot be removed until uncovered by the door and the lid raised. The lid serves the purpose of 90 excluding extraneous matter.

What I claim is:

1. The combination with a car having a door opening, of a door-receiving shoe, below said opening, in the form of a box 95 open above and closed otherwise and secured to the car wall by bolts having countersunk heads and nut-receiving threaded ends projecting into the box, and a door adapted to cover, when closed, the opening in said box, 100 whereby the nuts are inaccessible while the door covers said opening.

2. The combination with a railway car and its sliding door, of a hollow guide shoe, for the lower side of the door, provided 105 with a hinged lid adapted to open upwardly and excluding extraneous matter.

3. The combination with a freight car and its sliding door, of a shoe, for holding the lower side of the door in its proper plane, 110

made in the form of a box open upwardly only and having its outer wall projecting upward alongside the plane of the door, and non-rotary bolts passing outward from the car wall into the box and secured by nuts in the latter.

4. The combination with a railway car

and its sliding door, of a hollow guide shoe, for the lower side of the door, provided with a lid adapted to exclude extraneous matter ¹⁰ from said guide shoe.

In testimony whereof I hereunto affix my signature.

FRANK J. GILROY.
